EUGENE D. BALDWIN, OF EAST ORANGE, NEW JERSEY.

MECHANICAL TALLY.

1,271,992.

Specification of Letters Patent.

Patented July 9, 1918.

Application filed May 4, 1917. Serial No. 166,300.

To all whom it may concern:

Be it known that I, EUGENE D. BALDWIN, a citizen of the United States, residing at East Orange, in the county of Essex and 5 State of New Jersey, have invented certain new and useful Improvements in a Mechanical Tally; and I do hereby declare the following to be a full, clear, and exact description of the invention, such as will enable others skilled in the art to which it 10 appertains to make and use the same, reference being had to the accompanying drawings, and to characters of reference marked thereon, which form a part of this specification.

The present invention relates, generally, to a pocket counting device or tally keeper; and the invention has reference, more particularly, to a simple, cheap, compact and 20 easily operated tally keeper or counting device which may be readily carried in the pocket of the user.

The invention has for its principal object to provide a very simple and compact 25 construction of mechanical counting or tallying device providing a comparatively large total counting capacity notwithstanding its small bulk, and which may be quickly, easily and accurately operated by 30 a very simple movement while in the hand of the user.

The invention has for a further object to provide a very simple and easily operated resetting or wipe-out mechanism for returning 35 the counting mechanism to initial counting relation.

Other objects of the present invention, not at this time more particularly enumerated, will be clearly understood from the 40 following detailed description of the same.

With the various objects of my present invention in view, the same consists, primarily in the novel construction of counting or tallying device hereinafter set forth; and the invention consists, furthermore, in the novel arrangements and combinations of the various devices and parts, as well as in the details of the construction of said devices and parts, all of which 50 will be hereinafter more fully described, and then finally embodied in the claims appended hereto.

The invention is clearly illustrated in the accompanying drawings, in which:—

55 Figure 1 is an obverse face view of the

novel counting or tallying device, and Fig. 2 is a reverse face view of the same.

Fig. 3 is a reverse face view of the device, with the cover of the casing removed to show the interior mechanism; and Fig. 60 4 is an obverse face view of the same with the casing shown in section and disclosing the interior mechanism, both of said views being drawn on an enlarged scale.

Fig. 5 is a transverse section of the device, taken on line 5—5 in said Fig. 3, looking in the direction of the arrow *x*; and Fig. 6 is another detail transverse section of the same, taken on line 6—6 in said Fig. 3, looking in the direction of the arrow *y*. 70

Similar characters of reference are employed in all of the hereinabove described views to indicate corresponding parts.

Referring now to said drawings, the reference character 1 indicates the face wall 75 of a casing, 2 the marginal side walls thereof, and 3 the cover-plate thereof, which is secured in its closed relation by means of screws 4, or any other suitable fastening means. The reference character 5 indicates 80 a carrier-hub, provided at its opposite ends with journal studs 6, which are journaled in oppositely positioned bearing openings 7, respectively provided in said face wall 1 and in said cover-plate 3 of the casing. 85 Said carrier-hub 5 is provided, intermediate its ends, with an annular separating-flange 8. Vertically movable through said hub 5 is a stop-pin 9, the outer end of which is normally engaged in a receiving socket 10 90 formed in the inner surface of said face wall 1 of the casing, said stop-pin 9, when so engaged tending to normally retain said carrier-hub 5 against rotary movement. Said stop-pin is yieldably maintained in engagement with said receiving-socket 10 by means of a compression spring 11, mounted against the inner end of said stop-pin, between the same and the inner side of said cover-plate 3. 100

Mounted so as to rotate upon said carrier-hub 5, at one side of said separating-flange 8, between the latter and said face wall 1 of said casing, is a unit counting wheel 12. Said unit counting wheel 12 is 105 provided on its periphery with fifty transmission teeth 13, one of which, indicated by the reference character 14, constitutes a carrying-tooth and which is constructed to be of greater depth than its fellow teeth. 110

Fixed upon the outer face of said unit counting wheel so as to be rotated therewith, is a number-disk 15, preferably made of white celluloid, or some such material, and upon which are inscribed the unit counting numerals as shown. Said face wall 1 of said casing is provided with a suitably positioned opening or window 16, through which, upon operation of the device, the 10 said unit counting numerals are successively disclosed as the count or tally is proceeded with.

Mounted so as to rotate upon said carrier-hub 5, at the opposite side of said separating-flange 8, between the latter and said cover-plate 3 of said casing, is a "fifty" counting wheel 17. Said "fifty" counting wheel is provided on its periphery with fifty transmission teeth 18. Said "fifty" counting wheel 17 is smaller in diameter than said unit counting wheel 12, so that the teeth of the latter are spaced concentrically within or to the rear of the series of teeth of the latter, but in radial alinement therewith. 20 Fixed upon the outer face of said "fifty" counting wheel, so as to be rotated therewith, is a number-disk 19, preferably made of white celluloid, or some such material, and upon which are inscribed counting numerals indicating "hundreds" as shown. Said cover-plate 3 of said casing is provided with a suitably positioned opening or window 20, through which, upon the operation of the device, the said "hundreds" counting numerals are successively disclosed as the 25 count or tally is totaled thereby. The total tally, as recorded by said "hundreds" counting numerals, is maintained by means of fixed "tens" numerals 00 and 50 which are inscribed on the exterior of said cover-plate 3 adjacent to or on the right hand margin of said opening or window 20, and which combine with the "hundreds" counting numerals to give the total amount of the tally 30 in "hundreds" and "tens."

The means for preventing back-lash or improper directional movement or rotation of the respective counting wheels 12 and 17, comprises a spring-arm 21, the same being secured by a rivet 22, or otherwise, to the inner side of said marginal side walls 2 of said casing. The downwardly projecting end of said arm 21 is bifurcated to provide a pair of inwardly projecting spring dogs, 23 and 24 respectively, the free ends of which respectively engage the teeth of said counting-wheels so as to obstruct backward movement of the latter, while yielding of a proper forward movement of the same.

60 The reference character 25 indicates a push-pawl for operating the counting wheels. Said push-pawl is provided at its inner or lower end with a nosing 26 of sufficient width as to adapt the same to engage 65 simultaneously the teeth of both counting-

wheels in carrying over units into hundreds in totaling the tally or count. Said push-pawl is provided at its upper end with an exteriorly extending portion 27, which projects through a suitably disposed opening 28 70 in the marginal side walls 2 of said casing, and the same is provided upon its outer end with a turned over lip 29, forming both a finger-piece and a stop for limiting the downward movement of said push-pawl. 75 Said push-pawl is further provided at one side with a shoulder 30, which, by engagement with one of the fastening screws 4, or an equivalent means, limits the upward movement of the same, and determines its 80 initial position. Said pawl is controlled by an obliquely disposed pull-spring 31, one end of which is anchored over an anchor-stud 32 affixed to and projecting transversely from the inner side of said face wall 85 1 of said casing, and the other end of which is anchored over a coupling stud 33 projecting laterally from the body of said pawl. Said pull-spring 31 serves not only to retract said push-pawl after the downward 90 operative movement of the same, but also serves, by reason of its oblique disposition, to constantly pull said pawl toward the counting wheels, so as to maintain its nosing 95 26 in operative relation to and engagement 100 with the teeth of said counting-wheels, since such oblique pull of the spring tends to move the pawl laterally toward the counting-wheels while at the same time moving the same upward longitudinally.

In their initial position the respective counting-wheels 12 and 17 are so positioned as to expose through the openings or windows 16 and 20 their zeros. The zero of the "fifty" counting wheel is initially opposite the "tens" zeros inscribed on the cover-plate adjacent to the window 20. In using the counting or tallying device, the push-pawl 25 is pressed downward into the casing, and thereby the nosing 26, in engagement 105 110 with the teeth of the counting wheel 12 moves the same forward one interval, thus causing the unit "1" to appear in the window 16. The pawl is then released so that the pull-spring 31 can retract the same to initial 115 position. This operation is repeated in counting or tallying each unit until the numeral "49" appears in the window 16, whereupon the push-pawl, when retracted to initial position, engages by its nosing 26 120 125 the carrying tooth 14. Since the said carrying tooth 14 has a depth greater than its fellows, the lateral inward swinging movement of the pawl nosing is increased by engagement therewith so that said nosing is thereby permitted to engage simultaneously 130 a tooth 18 of the "fifty" counting wheel 17. When the push-pawl 25 is now pushed downward it rotates the unit wheel 12 one interval, thus completing the rotation there-

of and completing a count or tally of fifty, and at the same time rotates the "fifty" counting wheel one interval. It thus causes the zero of the unit counting wheel 12 to 5 again appear at the window 16, while the zero of the "fifty" counting wheel 17 moves forward one interval and alines itself with the "tens" indication "50" inscribed on the cover-plate 3 adjacent to the window 20, thus 10 indicating a total count of fifty. As the operation of tallying or counting is continued, and the unit wheel again completes a revolution indicating the counting of an additional fifty units, the "fifty" counting 15 wheel 17, by virtue of the above described carrying operation is again moved one interval, this movement causing the zero thereof to move away from the window 20 and out of registration with the "tens" indication "50" inscribed on the cover-plate 3, while the numeral "1" of the "fifty" counting-wheel is disclosed through the window 20 and registered with the "tens" indication "00" inscribed on the cover-plate 3, thus 20 indicating a total count or tally of "100." And so these operations are continued until the "fifty" counting wheel has completed its revolution, whereby a total tally or count of "2500" brings the wheels back to normal initial 25 starting points. It will thus be seen that the unit counting wheel moves or rotates at the ratio of fifty to one relative to the "fifty" counting wheel. While such a ratio is preferable for ordinary use and 30 limits the capacity of total registered count or tally to "2500", I do not wish myself to be understood as limiting my invention to such ratio, as the same may be altered without departing from the principles of my invention, and the ratio of movement of the 35 respective counting wheels is dependent only on the number of teeth with which the unit wheel is provided, and, within practical limits, this may be varied on the decimal basis from 5 to 100. If the unit wheel had 40 5 teeth its ratio of movement relative to the other wheel would be five to one, and a very small total tallying capacity would result whereas if the unit wheel had 100 teeth 45 its ratio of movement relative to the other wheel would be one hundred to one, and a comparatively large total tallying capacity 50 would result.

The means for wiping out the total count 55 or tally and resetting the device to initial counting position comprises the following elements: Connected with said spring-arm 21 is an upwardly projecting end 34, from the inner side of which projects inwardly a 60 positioning pin 35. Connected with the outer side of said portion 34 of the spring-arm 21 is an outwardly projecting push-button 36. Connected with the one of the teeth of said unit wheel 12 is a stop-pin 37. 65 Slidably mounted in openings provided in

said carrier-hub 5 are a pair of laterally movable dogs 38, which project outwardly from the circumference of said carrier-hub. Said dogs 38 are normally pressed outward by springs 39, and are yieldably backed by 70 said springs. Formed in the hub-portion 12' of said unit counting wheel 12 is a notch providing a shoulder 40 at one end, the back 41 of said notch curving inwardly to meet tangentially the circumference of said carrier-hub. In like manner, formed in the hub-portion 17' of said "fifty" counting wheel 17 is a similar notch providing a shoulder 42 at one end, the back 43 of said notch curving inwardly to meet tangentially 75 the circumference of said carrier-hub. One of said dogs 38 engages operatively the shoulder 40 of said unit wheel 12, and the other dog engages operatively the shoulder 42 of said "fifty" counting wheel 17. Projecting from and secured to that journal stud 6 of said carrier-hub 5 which projects through the cover-plate 3 is a screw-threaded shank 44 upon which is secured a turning-knob 45. When it is desired to reset the 80 counting wheels, the push-button 36 is pushed inwardly. This flexes inwardly the portion 34 of the spring-arm 21 and thrust inward the positioning pin 35. Now the turning-knob 45 is utilized to rotate the carrier-hub 5, and the movement of said carrier-hub is imparted to said counting-wheels 12 and 17 by the engagement with the respective shoulders 40 and 42 of the dogs 38, consequently rotating the said counting 85 wheels until the stop-pin 37 is arrested by engagement with said positioning pin 35 which has been interposed in its path. When the carrier-hub 5 is thus rotated the stop-pin 9 rides out of the receiving socket 10 90 and moves around with the hub until the same completes its rotation, whereupon it again is forced by its spring into said receiving-socket. When the counting wheels are arrested by engagement of the stop-pin 9 with the positioning pin the same have been 95 returned to initial counting position. When, during the normal counting movements of the counting wheels, the same rotate upon the stationary carrier-hub 5, the tangential backs 41 and 43 of the respective notches of the same ride over the dogs 38, and force the same backwardly into the carrier-hub, so it will be readily apparent that said dogs 38 do not interfere with the normal rotation 100 of said counting-wheels upon the carrier hub when the latter is stationary.

I am aware that some changes may be made in the various arrangements and combinations of the several devices and parts, 105 as well as in the details of the construction of the same, without departing from the scope of my present invention as defined in the appended claims. Hence, I do not limit my invention to the exact arrangements 110

and combinations of the various devices and parts as set forth in the foregoing specification, nor do I confine myself to the exact details of the construction of said parts as 5 illustrated in the accompanying drawings.

I claim:-

1. A mechanical tally comprising a casing, a unit counting wheel, a total counting wheel, said unit counting wheel and total 10 counting wheel being mounted back to back within said casing so that the unit count is disclosed through one side of said casing and the total count through the other side of said casing for independent reading

15 thereof, and an actuating device for mutually operating said counting wheels projecting from the periphery of said casing.

2. A mechanical tally comprising a casing, a unit counting wheel for indicating 20 successive unit counts, a total counting wheel for indicating a multiplication of completed series of unit counts, said casing

having separate apertures through which the numeral indications of said respective wheels may be respectively and independently read, the outer surface of said casing adjacent to said total wheel aperture having fixed numeral indications which are successively combined with the disclosed numeral of said total counting wheel upon the step 25 by step movement of the latter for the purpose of registering totals including the transferred units tallied by one complete revolution of the unit counting wheel, and means for mutually actuating said counting 30 wheels.

In testimony, that I claim the invention set forth above I have hereunto set my hand this 1st day of May, 1917.
